UNITED STATES PATENT OFFICE

WILLIAM T. GALLAGHER, OF RICHMOND, VIRGINIA.

SWINGING SCAFFOLD.

1,115,803.

Specification of Letters Patent.

Patented Nov. 3, 1914.

Application filed September 26, 1913. Serial No. 792,021.

To all whom it may concern:

Be it known that I, WILLIAM T. GALLAGHER, a citizen of the United States, residing at Richmond, in the county of Henrico and State of Virginia, have invented new and useful Improvements in Swinging Scaffolds, of which the following is a specification.

This invention relates to scaffolds and 10 more particularly to swinging scaffolds.

In using the ordinary type of swinging scaffold on buildings with gable roofs it is either necessary to have one or two stages in operation or to shift the scaffold so as 15 to paint the wall near the eaves. This all takes considerable time and trouble and is obviated in the use of the present construction whose object it is to provide a scaffold having inclined stages at opposite ends of 20 the scaffold with folding steps thereon which may be arranged out flat and in alinement with the main portion of the scaffold so as to increase its length when necessary.

Another object of the invention is the 25 provision of a scaffold constructed of hinged sections, two of which are adapted to be arranged in alinement with the other section or folded to produce inclined stairs adapted to be raised or lowered independent 30 of the other section.

Further objects of the invention will appear as the following description is read in connection with the accompanying drawing, which forms a part of this application, 35 and in which:

Figure 1 is a perspective view showing the application of the scaffold to a gable roof. Fig. 2 is a detail longitudinal section taken through the scaffold when in the position 40 shown in Fig. 1. Fig. 3 is a similar view showing the step sections of the scaffold alined. Fig. 4 is a detail top plan view showing the parts in alined position. Fig. 45 5 is a transverse section showing the position of the bumper.

Referring more particularly to the drawing, the scaffold is constructed of the hingedly connected sections 1, 2 and 3. The section 1 is constructed in the form of an ordinary 50 swinging stage having the stiles 4 and 5 connected together by the rungs 6 upon which is mounted the platform 7, while the sections 2 and 3 are hinged to the end rungs of the section 1 and have their overlapping

ends 8 notched, as shown at 9, to engage the 55 second rungs of the section 1, so as to prevent the outer ends of the sections 2 and 3 from raising beyond alinement with the section 1 and so as to lock all of the parts in alinement when the entire scaffold is supported from the outer ends of the sections 60 2 and 3. The sections 2 and 3 each comprise separate stiles 10 and 11 held together in spaced relation by the rungs 12 and being provided with a folding platform generally 65 indicated at 13. This platform is constructed of a plurality of links 14 hinged together and carrying the platform boards 15 which overlap and are supported directly upon the stiles 10 and 11. The links, as 70 shown in Fig. 4, are pivoted upon the end rung 6 of the section 1 and are arranged in connected pairs upon opposite sides of the sections 2 and 3, each pair being connected with the adjoining pair and the farther link 75 of each pair having an extension 16 provided with a notch 17 in its end adapted to engage one of the rungs 12 which connect the stiles of said sections.

In the position shown in Fig. 3 the 80 notched end of the farther link of the first pair is arranged to engage the next inner rung 12, as shown in Fig. 2, while the adjoining link of the second pair extends in a horizontal direction and its adjoining 85 link will be arranged in vertical position and engaged with the next outer rung. This arrangement is continued, as shown in Fig. 2, to produce steps, the platform boards of 90 which form treads and risers.

In hanging this scaffold it will be noticed that the section 1 is supported at opposite terminals by the usual roof hooks 18, block and falls 19 and stile engaging yokes 20 which are arranged at each end of the section and that the sections 2 and 3 are supported by similar devices connected to their outer ends. By this arrangement it will be noticed that the center section may be raised or lowered independently of the mechanism 100 for supporting the outer ends of the sections 2 and 3 and that these sections will swing inwardly or outwardly in accordance with the raising and lowering of the section 1, although their fixed relation to the 105 section 1, as shown in Fig. 1, may be maintained by manipulating the block and falls supporting the outer end of the said sections.

The present device is not only adapted to be used as a swinging scaffold for gabled roofs but may be also used as an ordinary swinging scaffold by supporting the entire structure from the outer ends of the sections 2 and 3, the extensions 8 engaging the second rungs of the section 1 and holding all of the parts in alinement. Also it will be clearly understood how the device may be used as a plasterer's scaffold by simply joining the two sections with a rope or cable tight to the lower rungs of each and stretched between said sections. The principal object of the invention, however, is its adaptability to all kinds of painting work where scaffolds are needed.

The bumper shown in Fig. 5 at 22 is preferably arranged at the ends of the sections 1 and 2 so as to hold the scaffold separated from the wall being painted. This bumper comprises a rod having springs 23 arranged to engage the stiles of the sections and being provided with hooks 24 through which the rod passes so as to prevent vertical displacement of the bumper. The springs may be pressed within the bumper so as to permit the passage of the rod through the hooks 24, as will be readily understood.

What is claimed is:—

1. A scaffold platform comprising a center section, end sections hinged together and

folding sectional platforms arranged on said end sections and adapted to be arranged in the form of stairs.

2. A scaffold platform comprising a center section having a platform, end sections hinged to said center sections, folding sectional platforms for said end sections, and means to support the folding platform in stair forming position.

3. A scaffold platform comprising a center section, end sections hinged thereto, independent means for supporting the center and end sections, folding sectional platforms upon said end sections, and means for supporting the platforms in step forming position independent of their relation with the center section.

4. A scaffold platform comprising a center section, end sections hinged to the center section, folding sectional platforms carried by the end sections, means for supporting the platforms in step forming position, and means for preventing the outer sections from raising at their outer ends beyond a position where the sections are alined.

In testimony whereof I affix my signature in presence of two witnesses.

WILLIAM T. GALLAGHER.
